UNITED STATES PATENT OFFICE.

ADDISON B. CARLL, OF NEW YORK, N. Y.

BARREL-FILLER.

1,233,024.

Specification of Letters Patent. Patented July 10, 1917.

Application filed April 29, 1916. Serial No. 94,473.

To all whom it may concern:

Be it known that I, ADDISON B. CARLL, a citizen of the United States, residing at New York, in the county of New York and 5 State of New York, have invented a new and useful Barrel-Filler, of which the following is a specification.

The present invention relates to an improvement in barrel fillers, and has for an object to provide an automatic barrel filler for cutting off the flow of liquid when the barrel or container is filled to the desired height, and wherein the discharge of the fluid into the barrel is had from the lower end of a 15 nozzle, which projects into the bung, or top of the barrel.

Another object of the invention is to provide a nozzle, which is detachably mounted on the body of the filler, and which is interlocked or dis-engaged from the body by the rotation of the nozzle in either one direction, or the other. This object of the invention 20 contemplates the mounting of a float in one side of the nozzle, and providing a concentric connection between the laterally offset float and the body, so that the float may be free to rise and fall and control the self closing valve in the body, and at the same 25 time the nozzle may be readily turned in either direction to remove the nozzle or replace the same.

It is a further object of the invention to provide a discharge nozzle for barrel fillers, wherein the fluid is discharged from the 35 lower end of the nozzle and wherein an eccentric float chamber is disposed in one side of the nozzle, and has the opening thereof through the adjacent side of the nozzle slightly above the lower end thereof, so that 40 the suction created by the outflow of fluid into the barrel will not draw the fluid out of the float chamber to thus prevent the free action of the float. The float chamber is provided with a vertically movable float 45 which is suitably spaced from the walls of the float chamber to prevent sticking of the float, and providing for its free action.

Other objects and advantages of this invention will be more clearly brought out 50 from the following description of the present preferred embodiment of the invention, the same being disclosed in the accompanying drawings, wherein:—

Figure 1 is a side elevation of the improved barrel filler.

Fig. 2 is a longitudinal vertical section,

taken through the device and showing its application to a barrel.

Fig. 3 is a vertical transverse sectional view, taken through the apparatus on the 60 line 3—3 of Fig. 2.

Fig. 4 is a transverse vertical sectional view through the body portion of the filler on the line 4—4 of Fig. 2.

Fig. 5 is a transverse horizontal sectional view, taken on the line 5—5 of Fig. 2, showing the top of the eccentric float chamber and concentric socket leading therefrom, and showing in section the protecting tube for the float connecting wire. 65

Fig. 6 is a similar view taken on the line 6—6 of Fig. 2, below the top of the float chamber and disclosing the float therein, and the lateral guides or spacers carried by the float. 70

Fig. 7 is a bottom plan view of the nozzle showing the crescent shaped outlet opening.

Fig. 8 is a detail top plan view of the latch lever employed for releasing the self closing valve in the body, and showing in top 80 plan the adjustable counterweight in its outermost position.

Fig. 9 is a bottom plan view of the same, showing the anti-friction shoulder for supporting and releasing the self closing valve. 85

Fig. 10 is a side elevation of the latch lever, partly in section, showing the roller, and showing the adjustable counter-weight, the dotted lines showing the position of the weight when moved into its innermost position. 90

Referring to these drawings, wherein like parts are designated by similar numerals of reference, 15 designates the body of the filler, which is in the form of a valve casing having 95 an intermediate horizontal web 16 suitably apertured, and provided with an upstanding valve seat about the aperture. A valve 17 is adapted to engage the valve seat and be held thereto by a spring 18, which surrounds the upstanding valve stem 19. The valve stem 19 passes upwardly into a guide 20 formed within a cap 21 detachably placed upon the upper end of the body 15, and preferably engaging in 105 screw threaded relation with the body, as shown in Fig. 2. The spring 18 bears at one end against the valve 17 and at its opposite end against the guide 20 so as to normally urge the valve 17 against the valve 110 seat. A suitable inlet nipple 22 leads from the rear side of the body 15 above the web

16, and is adapted for connection with a flexible hose, or the like, through which liquid is conveyed to the filler.

The stem 19 of the valve projects downwardly from the valve 17 through the opening in the web 16, and is seated in a stepped bearing or guide 23, upstanding from the lower wall of the body 15. The guides 20 and 23 hold the valve stem 19 in true vertical alinement, so as to insure the true seating of the valve 17 on the valve seat, and to prevent lateral displacement of the valve 17, when operated by the mechanism hereinafter described. The lower end of the valve stem 19 has an outstanding flange or rim 24 constituting an abutting shoulder against which the finger 25 is adapted to strike for raising the valve stem 19 and opening the valve 17. The finger 25 is fixed upon a transverse shaft 26 extending horizontally and transversely through the body 15 behind the valve stem 19. As shown in Fig. 4, one end of this shaft 26 is journaled in a bearing 27 in the form of a boss projecting inwardly from the side of the body 15, and the opposite end of the shaft 26 is journaled in an inwardly projecting sleeve or boss 28 preferably integral with a detachable cap 29 fitted in the opposite side of the casting 15. The finger 25 is in the form of a two-part or forked member, each part of which engages against one side of the valve stem 19, so that the finger 25 straddles the valve stem 19 and engages the flange or abutment 24 at the opposite sides of the valve stem, so as to equalize pressure thereagainst and prevent lateral thrust upon the valve and its stem, when the shaft 26 is turned to raise the finger 25 against the tension of the spring 18. The outer end of the shaft 26 has a rectangular shank 30 lying adjacent to the side of the body 15 and adapted to receive the angular socket 31 of an arm 32. As shown to advantage in Fig. 4, the arm 32 has a flat inner side adapted to lie close against the side of the body 15, and as shown in Fig. 1, to move against a flat segmental guide or bearing 33 projecting laterally from the body 15 and terminating at its rear end in a stop 34. The stop 34 projects laterally and outwardly from the guide 33 and engages the rear side of the arm 32 when the latter is in its lowermost position, as shown in Figs. 1 and 4, and in position to admit the seating of the valve 17 under the action of the spring 18. A retaining nut 35 is detachably mounted upon the threaded outer extremity of the shaft 26, the nut bearing against the angular socket 31 of the operating arm to hold the latter on the shank 30 of the shaft.

The lower end of the body 15 is offset forwardly as at 36 and is internally threaded at its lower end to receive a tubular nozzle 37, which is detachably mounted upon the

body 15 by reason of its threaded engagement therewith. This nozzle 37, as may be best seen from Figs. 2 and 5, has an eccentric float chamber 38 mounted in one side thereof and extending substantially throughout the entire length of the nozzle 37, although the length of the float chamber is immaterial. The float chamber is closed at its lower end by a plug 39 threaded into the lower end of the chamber 38, as shown in Figs. 2 and 7, to entirely close the lower end of the float chamber, so that the fluid passing downwardly out of the nozzle 37, through the crescent shaped outlet thereof, cannot by suction disturb the contents of the float chamber. The outer side of the float chamber 38 preferably merges into the adjacent side of the nozzle 37, as shown to advantage in Figs. 6 and 7, and this common side of the float chamber and the nozzle is provided with one or more openings 40 adjacent the lower end of the nozzle 37 to receive fluid from the barrel when the latter is nearly filled, and to admit the fluid to the float chamber. Within the chamber 38 is a float 41. As shown in Figs. 2, 3 and 6, the float is relatively small in diameter, as compared with the inner diameter of the chamber 38, so as to provide a space between the float and the inner wall of the chamber. The float is held concentric within the chamber 38 by guides or spacers 42, in the form of wings or lugs outstanding radially from at least three sides of the float, and being equally spaced thereabout so as to hold the float centrally in the chamber, as shown in Fig. 6. The float is thus permitted to move freely up and down within the chamber 38, without liability of sticking or producing undue wear or friction on the float and chamber. The float 41 is connected by a suitable connecting element 43, such as a wire or rod as shown, with a latch lever 44 pivoted upon the body 15 to control the operation of the self-seating valve 17. The rod or connecting element 43 extends down into the nozzle 37, and in order to protect the rod 43 from contact with the fluid passing down through the body and nozzle, an inclosing tube 45 is employed which projects downwardly from the body 15 and opens through the body thereof immediately beneath one end of the latch lever 44.

In order that the nozzle 37 may be turned either to the right or left, and rotated a considerable number of times, to entirely detach the nozzle from threaded engagement with the body 15, or to bind the nozzle tightly in the lower end of the body 15, it is essential to so arrange or dispose the connection between the float 41 and the latch lever 44, and to so dispose and arrange the protecting tube 45 for the connecting wire 43, as to admit of its rotative movement without the necessity of disassembling the entire apparatus.

With this purpose in view, the present invention provides an upstanding socket or nipple 46 on the top of the float chamber 38, which socket 46 is located concentric to the nozzle 37. The connecting wire or element 43 is secured to the float 41 at one side thereof in vertical alinement with the socket 46, as shown in Fig. 2 of the drawings, and is secured to the float preferably by an eye 47, which passes through one of the wings or radiating spacers 42 at the upper end of the float 41. The socket 46 is adapted to slidably and rotatably receive the lower end of the protecting tube 45 therein. The tube 45 is threaded at its upper end into a threaded socket 48 opening downwardly through the upper wall of the offset portion 36 of the body. Thus, when the nozzle 37 is turned to screw up or unscrew the same, the nozzle is free to rotate, the axis of rotation being coincident with the axis of the connecting rod 43 and the protecting tube 45 to admit the free turning of the socket 46 about the lower end of the tube 45.

The upper side of the casing 15, constituting the top of the offset portion 36, is provided with a pair of spaced apart transversely extending ears 49 and 50. As shown in Figs. 1, 2 and 3, the spaced apart ears provide a transverse passage or channel to receive therein the outer long arm of the latch lever 44. The lever 44 is fulcrumed upon a pivot bolt or pin 51 passing transversely through the outer ends of the ears 49 and 50 to dispose the outer end of the latch lever immediately over the socket 48 and tube 45, which is fitted therein. This outer end of the latch lever is hooked or arched downwardly as at 52 to receive thereover an upper eye 53 formed upon the upper end of the connecting element or wire 43. This latch lever 44 is provided with an inner horizontal arm 54 adapted to support the counter-weight 55, and also has a depending vertical arm 56 having a supporting shoulder 57 on its lower end facing outwardly to receive thereagainst the inner edge of the valve controlling arm 32, as shown in dotted lines in Fig. 1, and in section in Fig. 3.

The counter-balancing weight 55 is adjustable so as to vary the effective weight of the float 41 when surrounded by the fluid. The counter-weight 55 may be of any desired shape, form or size, but for the purposes of illustration, is shown in the present instance, as comprising a flat relatively thin disk pivoted at its central portion upon the top flat face of the horizontal arm 54 of the latch lever by means of an adjustable screw 58 beneath which is placed a spring washer 59, the ends of which are offset from one another out of the plane of the washer to yieldingly hold the disk against the arm 54. One edge of the disk is provided with the

body of the weight, the same being in the form of a substantially semi-circular block or thickened flange upstanding from the disk, and being of sufficient size to counterbalance the float 41 to the desired extent. The outer edge of the disk and the outer face of the body portion of the weight 55 are both serrated or milled to provide roughened finger engaging surfaces admitting of the easy turning of the disk upon the pivot screw 58, so as to turn the body of the weight 55 into various distances outwardly from the pivot pin 51 of the latch lever to thus vary the weight pressure on the horizontal arm of the lever. In Fig. 10 there is shown in dotted lines the innermost position of the weight 55, showing that the weight is disposed substantially in the vertical plane of the pivot 51 of the latch lever, so that the effective weight of the horizontal arm 54 is practically eliminated.

The depending vertical arm 56 of the latch lever carries therein an anti-friction roller 60, which projects slightly above the supporting shoulder 57, and is adapted for direct contact with the opposite faces and the inner edge of the valve arm 32. It will be noted that the lower outer side of this arm 56 is beveled inwardly and downwardly so as to expose a substantial portion of the periphery of the roller 60 and to bring the roller 60 into contact with the arm 32, when the latter is swung up to open the valve 17. When the device is set in the open position, the parts assume the positions shown in Fig. 3 of the drawings. In this arrangement of the parts, the float 41 holds the latch lever down in locked position to secure the roller 57 beneath the arm 32 and hold it in raised position against the tension of the spring 18. As soon as the float 41 is raised a sufficient distance, the weight 55 advances the lever 44 during the upward movement of the float to take up any slack therebetween, and swings the supporting arm 56 inwardly a sufficient distance to admit the release of the valve arm 32 from the shoulder 57. When this condition arises, the arm 32, under the action of the spring 18, presses the roller 57 down to retract the latch lever, the anti-friction roller admitting of the easy operation of the parts and offsetting undue wear between the shoulder 57 and the inner edge of the arm 32. Thus, as the friction is reduced, the action of the latch lever is a quick one, so that the arm 32 is quickly released and the valve 17 immediately closed upon the raising of the float to the predetermined height. The counter-weight 55 may be adjusted into various positions to regulate the desired counter-action upon the float 43 to increase or decrease the effective weight of the latter, so as to admit of the fine adjustment of this improved barrel filler, irrespective of the specific gravity, or

other characteristics of the liquids, which are passed through the device.

As shown in Fig. 2 of the drawings, the nozzle 37 is preferably provided with an adjustable support 61 in the form of a split sleeve having outstanding ears 62 at one side through which is passed a clamping bolt 63 for contracting the ears and binding the sleeve 61 on the nozzle. Depending 10 legs 64 radiate from the sleeve 61 and are adapted to rest upon the head 65 of a barrel 66. The legs 64 are spaced about the nozzle 37 to admit the insertion of the nozzle downwardly through a bung, or an opening 67, 15 in the head 65 of the barrel, and to support the nozzle at the desired height through the opening 67.

From the above description, taken in connection with the drawings, it is believed 20 that the operation of the device will be clearly understood, for, when the parts are in set position as shown in Fig. 3, and in dotted lines in Fig. 1, the valve 17 is open so that the fluid is permitted to pass freely 25 from the inlet nipple 22, through the body 15, and outwardly through the lower crescent shaped end of the nozzle 37. The tube 45 prevents the liquid from entering the float chamber at the top thereof, the lateral 30 disposition of the openings 40 in the side of the float chamber prevents the suction of the outflowing liquid from effecting the contents of the float chamber. The roller 60 supports the arm 32 in horizontal position 35 at the forward end of the guide 33 to hold the finger 25 up against the abutment 24, and supports the valve 17 above the seat against the tension of the spring 18. As soon as the float 41 is raised sufficiently to 40 relieve the outer end of the latch lever 44 of the weight of the float, the weight 55 swings the latch lever 44 upwardly at its outer end and moves the shoulder 57 from beneath the arm 32. The arm 32 now forces 45 the roller 60 inwardly from beneath the arm, the roller reducing frictional contact between the arms 56 and 32, and admitting of the quick action of the arm 32 in swinging downwardly and backwardly to seat the 50 valve 17. Should it be found necessary to adjust the counter-weight 55, the same may be turned by hand about its pivotal support 58, so as to dispose the center of gravity of the weight 55 at the desired distance from the pivot pin 51 of the latch lever.

When it is desired to gain access to the 60 interior of the device, or to pack the same for shipment, or for any other reason to separate the nozzle from the body 15, it is only necessary to turn the nozzle upon the body to unscrew the nozzle therefrom, the float connection with the latch lever being concentric to the nozzle and the body 10, so that the parts will not be dislodged, and 65 will not have to be removed prior to the

turning of the nozzle. When the nozzle is unscrewed, it is only necessary to draw the same downwardly, so as to remove the socket from about the lower end of the tube 45, and withdraw the connecting element 43 from the lower end of the tube to entirely disconnect the nozzle from the body. It is, of course, understood that prior to the turning of the nozzle, the connecting wire 43 must be disengaged from the hooked end 75 70 of the latch lever.

In the present practical embodiment of the invention, from which the accompanying drawings have been made, the latch lever or pawl 44 is provided with spacing 80 bosses 68 at its opposite sides and through which the pivot pin 51 passes. The bosses take up the frictional contact between the lever 44 and the ears 49 and 50, and serve to steady the lever in its swinging move- 85

It is, of course, understood that various changes and modifications may be made in the above specifically described construction, without departing from the spirit of 90 this invention and being restricted only by the scope of the following claims.

What is claimed is:—

1. In a barrel filler, a body having a self-closing valve therein, a latch lever for holding the valve open, a detachable nozzle for securing to and removal from the body by the rotation of the nozzle in opposite directions, a chamber eccentric within the nozzle, a float in the chamber, and a wire 95 100 loosely connected to the float at one end and detachably and loosely connected to the latch lever at its opposite end to actuate the latter upon the predetermined movement of the float, said wire being concentric to the 105 nozzle to admit the free rotation of the same.

2. In a barrel filler, a body having a self-closing valve therein and means for controlling the valve, a detachable nozzle for securing to and removal from the body by the rotation of the nozzle in opposite directions, a float arranged in the nozzle eccentric thereto, and a wire loosely connected to 110 115 the float at one end and removably connected to said valve controlling means at its opposite end, said wire extending from one side of the float upwardly through the nozzle and the body in concentric relation to the 120 nozzle to admit the free turning of the nozzle in either direction.

3. In a barrel filler, a body having a self-closing valve therein, and a concentric tube depending therefrom, a nozzle screw 125 threaded into the lower end of the body, the nozzle having an eccentric float chamber in one side thereof provided with an upwardly opening socket concentric with the nozzle and adapted to slidably receive the lower 130

- end of said tube therein when the nozzle is screwed up into the body, a float in said chamber, a connecting wire for controlling said valve depending from the body through 5 said concentric tube and said concentric socket, and having a pivotal connection with one side of the float to admit the free rotation of the nozzle in opposite directions on the body to position and remove the nozzle.
- 10 4. In a barrel filler, a body having a self-closing valve therein and controlling means to hold the valve open, a nozzle carried by the body and adapted for detachment therefrom by the rotation of the nozzle, a tube 15 depending from the body and projecting into the nozzle concentrically thereof, a float mounted eccentrically in one side of the nozzle, and a connecting wire pivotally secured at its lower end to one side of said 20 float and extending upwardly and centrally in the nozzle and body through said tube, and having a detachable connection with said controlling means.
5. In a barrel filler, a body, a self-closing 25 valve on the body, a latch lever to hold the valve open, a hook on the outer end of said latch lever, a connecting wire having an eye at its upper end removably engaging said hook and depending downwardly through 30 said body, a protecting tube depending from said body about said wire, a nozzle threaded to the lower end of the body and provided with an eccentric chamber in one side thereof having an upwardly opening socket con- 35 centric with the nozzle and adapted to slidably receive the lower end of said tube when the nozzle is secured into the body, and a float mounted in said chamber and having a pivotal connection at one side with 40 the lower end of said connecting wire whereby to admit of the free rotation of the nozzle about the tube.
6. In a barrel filler, a body having a self-closing valve therein, a nozzle depending 45 from the body, a float mounted in the nozzle, a latch lever hinged to the outer side of the body and having connection with said float, and a counter-weight pivoted eccentrically upon the outer end of said latch 50 lever and adapted to turn in a horizontal plane to adjust the counter-balancing of the weight.
7. In a barrel filler, a body having a self-closing valve therein with an arm to open 55 the valve, a latch lever pivoted upon the body and having a supporting shoulder for engagement with said arm to hold the same when raised to open the valve, a float con-
- nected to the outer end of the latch lever, and a rotary counter-weight mounted upon 60 the inner end of said latch lever, and comprising a flat disk pivoted for rotation in a horizontal plane upon the end of the lever and having an eccentric enlargement adapted to be shifted toward and from the pivotal 65 support of the lever to vary the counter-balancing action thereof.
8. In a barrel filler, a body having a self-closing valve, a latch lever hinged to the body for controlling the action of the valve, 70 a float connected to one end of the latch lever, and a counter-weight carried upon the opposite end of the latch lever, said counter-weight comprising a flat disk pivotally mounted for rotation upon the inner end of 75 the latch lever and extending in substantially a horizontal plane, a spring washer bearing upon the upper side of said disk for yieldingly holding the same to the end of said lever and from accidental rotation, 80 and a body portion located eccentrically upon the disk and adapted to be shifted toward and from the pivotal support of the latch lever by the rotation of the disk, said washer yieldingly holding the disk from 85 turning when adjusted.
9. In a barrel filler, a body having a self-closing valve and an arm adapted to swing at the side of the body for opening said valve, a latch lever pivoted to the casing 90 and having a shoulder adapted to engage beneath said arm to support the same to hold the valve open, means for releasing the latch lever, and an anti-friction roller counter-sunk in the shoulder and bearing 95 against said arm to reduce frictional contact between the arm and shoulder, and admit the quick action of the arm and consequent quick closing of the valve.
10. In a barrel filler, a body having a self-closing valve therein and controlling means to hold the valve open, a nozzle detachably carried by the body and having a float chamber eccentrically therein, a float located within said chamber, a tube leading from 105 the chamber through the body exteriorly thereof, and a connection loosely engaged with the float and also detachably engaged with said controlling means.

In testimony, that I claim the foregoing 110 as my own, I have hereto affixed my signature in the presence of two witnesses.

ADDISON B. CARLL.
